UNITED STATES PATENT OFFICE.

RICHARD C. KAISER, OF NEW ROCHELLE, AND NICHOLAS J. MIANO, OF NEW YORK,
N. Y.; SAID MIANO ASSIGNOR TO SAID KAISER.

DISPLAY DEVICE.

1,313,897.

Specification of Letters Patent. Patented Aug. 26, 1919.

Application filed November 14, 1918. Serial No. 262,439.

To all whom it may concern:

Be it known that we, RICHARD C. KAISER and NICHOLAS J. MIANO, citizens of the United States, residing at New Rochelle, county of Westchester, and State of New York, and in the city, county, and State of New York, respectively, have invented certain new and useful Improvements in Display Devices, of which the following is a specification.

Our invention relates to the mounting and displaying of fabrics in the piece such as woolen goods, dress goods and the like, and is especially adapted for the display of woolen goods in the piece.

An especial object of our invention is the provision of means by which the woolen goods may be displayed without the necessity of the employment of an entire bolt of fabric for this purpose but which will give the same effect as to draping, etc., as if the whole bolt of cloth were employed.

An especial object of our invention is the provision of a mounting and display apparatus for the use of woolen goods merchants and merchant tailors, by which a number of woolen fabrics may be effectively and economically displayed.

At the present time it is the practice of merchant tailors and woolen goods' merchants to have in stock bolts or large pieces of fabrics which they intend to offer to prospective customers. These are kept stored upon shelves or tables and must be pulled out and shown one by one to the prospective customers. This is a time consuming operation, which speedily wearies the customer, as large bolts or pieces of fabric must be pulled out and shown one by one, and in addition, the customer fails to secure the proper appreciation of the goods submitted for his inspection because it is difficult to compare them, and the average customer is unable to spend sufficient time to properly look over the lines submitted to him. Furthermore, this is an expensive manner of keeping and displaying fabrics for the woolen goods' merchant or merchant tailor, as, to properly display fabrics in the piece, a large bolt of cloth must be handled at each inspection of the fabric.

According to our invention, a very simple and cheap device is provided which is suitable for the window, counter or floor display of fabrics in the piece and which not only

provides a convenient means for rapidly and efficiently displaying fabrics, but also for storing same in stock. Other objects of our invention will be set forth in the following description and drawings which illustrate preferred embodiments of our invention.

Figure 1 is a side view of our invention embodied in a swinging display rack.

Fig. 2 is a detail perspective view showing the specific construction of the holding brackets.

Fig. 3 is an elevation of our invention embodied in a stand for window display.

Fig. 4 is an end view of Fig. 3.

Fig. 5 is an end view of Fig. 6 showing a double display stand.

Fig. 6 is an elevation of Fig. 5.

In Figs. 1 and 2 a series of metal shafts 2, are supported at their tops and bottoms in metallic members 1 and 5 respectively, so that they are revolubly held. These shafts 2, as well as the parts 1 and 5, may be of any known metal construction which is not set forth in detail herein, because many well-known types may be employed because this is not in itself an essential part of our invention. Metallic frames 3 are secured in any suitable manner to the revoluble shafts 2, and are further connected thereto by the angle members 30, which further strengthen the structure.

A series of holding brackets 7, are connected to the metal frames 3. As shown more particularly in Fig. 2, these holding brackets 7 are composed of foundation members 9, which are preferably made of a single strip of metal, bent into shape, the general contour of each said foundation member 9, being that of a U on each side of the frame 3. The strips of metal of which the foundation members 9 are composed are preferably made quite resilient and springy. The foundation members 9 are secured to the tops of the frames 3 by any suitable means, such as spot-welding or the like. An upper horizontal clamping member 10, is secured to two of the foundation members 9 at each side of the frame 3, and has the general contour shown in Fig. 2, and is secured to the inner legs and outer legs of the foundation members 9, by spot-welding at substantially the points 12 and 14. These members 10 are also made of springy metal.

Side holding members 15 having the contour shown in Fig. 2 are secured by any

suitable means to the sides of the members 10 and the bottoms of the members 9 at each side of the frame. The holding brackets 7, can therefore, be made independent of the frames 3, and can be readily applied by spot-welding. The inner legs of the members 9 are also preferably connected to the bottoms of the frames 3, by connecting members 50, having the contour shown in Fig. 2 and which are preferably connected to the bottoms of the frames 3, by spot-welding. The side members 15 are preferably made of rigid metal, and are parallel to the upper and lower bars of the frames 3, so that the yield, if any, is in the resilient members, before mentioned.

Boards 8 having tapered lower ends are fitted into these brackets 7, and serve for holding a piece of fabric which can be draped over them so as to display the fabric to the prospective customer. In Figs. 3 and 4, the holding brackets are shown combined with a stand 31, and in Fig. 6, the stand 32 has a double set of these brackets 7. Rear brackets 7, can be arranged with respect to the front brackets in any pleasing arrangement so as to better display the goods. The structures shown in Figs. 3, 4, 5, and 6, are more adapted for window display while that shown in Figs. 1 and 2 is more adapted for show-room display. Of course, the various structures can be made up of parts so that they can be conveniently shipped, put together and taken apart again whenever desired.

We have shown a preferred embodiment of our invention but we do not wish to be limited to the details thereof, as numerous changes and omissions can be made without departing from its spirit.

We claim:

1. In combination, a frame having upper and lower bars and a bracket secured thereto, each said bracket comprising two foundation members having substantially U-shaped branches on each side of the said bars, the said branches being joined above the top of the uppermost of said bars and secured thereto, a substantially horizontal

holding member secured to said two foundation members and passing between the inner legs of the said U-shaped branches and the said bars, and side holding members secured to the bottoms of the said substantially U-shaped branches and to the said substantially horizontal holding members.

2. In combination, a frame having upper and lower bars and a bracket secured thereto, each said bracket comprising two foundation members having substantially U-shaped branches on each side of the said bars, the said branches being joined above the top of the uppermost of said bars and secured thereto, a substantially horizontal holding member secured to said two foundation members and passing between the inner legs of the said U-shaped branches and the said bars, and side holding members secured to the bottoms of the said substantially U-shaped branches and to the said substantially horizontal holding members, the said foundation members and the said horizontal holding member being springy and the said side member being rigid.

3. In combination, a frame having upper and lower bars, foundation members having branches on each side of the said bars of a substantially U-shape, the inner legs of the said branches meeting above the uppermost of the said bars and being secured to the top of the said uppermost bar, the bottoms of the said U-shaped branches extending substantially to the lowermost of the said bars, means for securing the inner legs of the said U-shaped branches to the said lowermost bar, a horizontal holding member secured to the outer legs of the said branches and passing between the inner legs of the said U-shaped branches and the uppermost of the said bars and located at substantially the level of the said uppermost bar, and side holding members secured to the side of the said horizontally holding members and the bottoms of the said branches.

In testimony whereof we hereunto affix our signatures.

RICHARD C. KAISER.
NICHOLAS J. MILANO.
